UNITED STATES PATENT OFFICE.

REUBEN H. SMITH, OF RUSSELLVILLE, ARKANSAS.

GRATE.

SPECIFICATION forming part of Letters Patent No. 445,575, dated February 3, 1891.

Application filed August 22, 1890. Serial No. 362,747. (No model.)

To all whom it may concern:

Be it known that I, REUBEN H. SMITH, a citizen of the United States, residing at Russellville, in the county of Pope and State of Arkansas, have invented a new and useful Grate, of which the following is a specification.

This invention has relation to grates; and the objects in view are to provide a grate so constructed as to obviate warping and to prevent the clogging of the air-spaces, and adapted to thoroughly consume any fuel that may be introduced therein.

With the above general objects in view the invention consists in certain features of construction hereinafter specified, and particularly pointed out in the claim.

Referring to the drawings, Figure 1 is a perspective of the grate constructed in accordance with my invention. Fig. 2 is a transverse section on the line α α of Fig. 1.

Like numerals of reference indicate like parts in all the figures of the drawings.

In practicing my invention I employ opposite end bars 1 and one or a series of intermediate similarly-disposed bars 2, located at suitable distances from each other and from the end bars. The opposite end bars 1 and intermediate cross-bars 2 are of V shape upon their upper edges when viewed in elevation, and consequently their under edges are converged toward their centers, or, in other words, are oppositely inclined from their ends to points near their centers. The under edges of the end bars 1 and also the intermediate cross-bars 2 are connected at their centers by a central longitudinal grate-bar 3, provided at intervals with transversely-disposed oblong openings 4.

At each side of the central grate-bar 3 the under edges of the bars 1 and 2 are provided with a series of offsets or steps 5 of uniform dimension and distances apart. The offsets or steps of the end bars agree or are longitudinally-opposite the offsets or steps of the intermediate bars, and each longitudinal series of offsets is occupied by a longitudinal grate-bar 6 of a thickness less than the distance between the offsets, so that the longi-

tudinal grate-bars aforesaid combine to form a series of shelves for the support of the fuel and at their outer edges air-spaces 7.

It will be noticed that the inner edge of each grate-bar is vertically-opposite or above the front edge of the grate-bar below the same. The grate is thus adapted to support the fuel without danger of the same falling through unburned, and can only be removed by the dumping of the grate or a raking of the same.

A grate thus constructed may be used for burning coal, coke, straw, cobs, and in fact any kind of fuel or waste material, and this too in a most thorough manner, in that it is contained within the grate until entirely consumed.

By reason of the several compartments formed by the transverse intermediate bars 2 a fire may be made in any one, two, or three of them, so that a greater or less heat may be generated either for heating or cooking purposes regardless of the aggregate size of the grate.

In practicing the grate may be and is preferably integrally cast, although I do not limit my invention to such. Aside from the bars 2 separating the grate into a system of fuel compartments, they also act as stays for the grate-bars and tend to decrease their liability to warp by excessive heat.

Having described my invention, what I claim is—

A grate comprising a series of intermediate and opposite end bars, each of which upon its under side is cut away or inclined in an opposite direction at each side of its center, a central bar having a series of perforations or openings connecting the series of bars at their centers, and a series of longitudinal grate-bars seated in the offsets and connecting the series of transverse bars, substantially as specified.

In testimony that I claim the foregoing as my own I have hereto affixed my signature in presence of two witnesses.

REUBEN H. SMITH.
